UNITED STATES PATENT OFFICE.

WILLIAM SUNDBERG, OF CHICAGO, ILLINOIS.

GRAIN-ELEVATOR AND THE LIKE.

1,294,566.

Specification of Letters Patent. Patented Feb. 18, 1919.

Application filed May 28, 1918. Serial No. 237,017.

To all whom it may concern:

Be it known that I, WILLIAM SUNDBERG, a citizen of the United States, and a resident of Chicago, county of Cook, and State 5 of Illinois, have invented certain new and useful Improvements in Grain-Elevators and the like, of which the following is a specification.

My invention relates generally to improvements in grain elevators and the like and has particular reference to improvements in methods and means for spouting or distributing grain and other similar materials.

For the sake of simplicity I shall refer 15 herein only to grain elevator construction, but it will be understood that when the term "grain" is used, other materials that can be handled in a like manner will be embraced in this term. When the term "legs" 20 is used in these specifications, it refers to bucket elevators of the type generally used in grain elevators and which, in the grain elevator business, are commonly known as legs.

25 In every grain elevator there is what is known as a work, working or operating house. Some grain elevators are of the type known as the work house type, in which all of the grain bins are in the work house, there 30 being no storage annex attached; in some large grain elevators, or in grain elevators of certain types, there are also buildings other than the work, working or operating house, which serve the same or similar purpose 35 but which are given a different name (for instance, river house). It is with this part of the grain elevator that this invention is concerned primarily and, therefore, that part only will be considered. The work

40 house or operating part of a grain elevator is used for the purpose of manipulating grain in various ways, as may be necessary in the blending or in the removal of the grain from bins, and the discharging thereof 45 to a number of different points as, for example, to elevator legs or belt or screw conveyors or other points, or merely for turning the grain over by emptying the grain from the bins and reëlevating it again to reduce its temperature.

50 Heretofore the general installation for accomplishing this purpose has comprised a number of portable spouts, which have been erected from time to time between certain of 55 the bin bottom turn head spouts, discharg-

ing from the bins to the points of discharge as, for example, the grate openings in the first floor. From these grate covered openings fixed spouts have been run to the legs or conveyers.

60 This system of distributing the grain requires a large amount of labor for the reason that these portable spouts must be knocked down and erected from time to time and also entails many other disadvantageous features which will appear more fully hereinafter.

65 One primary disadvantage of the portable spout has been that it is impossible to spout grain from certain of the bins to certain 70 desired openings simultaneously for the reason that the spouts would cross each other's path and thus interfere one with the other. In many instances, therefore, it has only been possible to spout grain in a single direction, 75 thus entailing great delay and cutting down the efficiency of the legs or conveyers by keeping one or more of them idle while the other was being run, which has heretofore greatly reduced the flexibility and efficiency 80 of the whole operating or working house. Also, another disadvantage of this system has been that on account of grain cleaning machines and dust pipes from same, and other obstructions between the first floor and 85 the bin bottom, it has been very difficult and sometimes impossible to spout grain from some of the bins to the desired first floor grating. Another disadvantage has been that it has been difficult to get around building 90 columns to the desired floor grating.

95 Another system of spouting grain used at times has consisted in individual spouts between bins and to certain points from which short portable spouts were run to the desired point. This system was not only expensive and difficult, in that an individual spout was run from each bin to a point, but also had the objection before mentioned of the portable spouts used therewith crossing 100 each other's path and hence preventing a simultaneous routing or spouting of the grain in a number of directions. Furthermore, because of the large amount of spouting required, and because of before mentioned obstructions, it was in some instances impossible to get all of the spouts in on account of lack of space.

105 The general objects of my invention are to provide a system of spouting grain whereby 110

the grain can be distributed from any of a number of bins to one or more discharge points, with the least amount of spouting, and preferably without any interference of 5 the spouting used to distribute the grain in other directions, and also to reduce the amount of labor required.

My invention consists generally in methods and means whereby the above named 10 objects, and other objects which will appear hereinafter, are attained, and my invention will be more readily understood by reference to the accompanying drawings which illustrate forms of my invention which I 15 consider the best at the present time.

Figure 1 is a plan view illustrating the first floor of a work or operating house equipped with spouting embodying my invention.

20 Fig. 2 is a vertical section (spouting in elevation) substantially on the line 2—2 of Fig. 1.

Figs. 3 and 4 are respectively a side elevation and an end elevation of spouting 25 unit D.

Figs. 5 and 6 are respectively a side elevation and an end elevation of spouting unit M.

Figs. 7 and 8 are respectively a side elevation and an end elevation of spouting unit N.

Elevations of units D, M and N are typical. Elevations of units A, B, C, E, F, G, H, J, L, and K are similar.

35 Fig. 9 is a fragmentary plan view of another work or operating house, first floor, equipped with a similar spouting system embodying my invention.

Fig. 10 is a view partly in section and partly in elevation, on the line 10—10, of 40 Fig. 9, but showing only spouting units R, S, T, U and V (other units being omitted for the sake of clearness).

Fig. 11 is a sectional elevation showing spouting units W, X, Y and Z.

45 Fig. 12 is an end elevation viewed substantially from the line 12—12 of Fig. 9, but showing only spouting units R, S, T, U, W, X and Y (columns and other parts of the building being omitted for the sake of clearness).

I will first describe that form of my invention shown in Figs. 1 to 8 inclusive. Therein 1 represents the work-house grain elevator building provided with a basement 55 2, first floor 3, and a plurality of grain bins, the bottom outlets of which have been numbered in the plan view from 4 to 49 inclusive. The bottom or outlet from each bin, as is best shown in Fig. 2, comprises a hopper portion 50, to which is secured a bin bottom gate 52, and a turn head spout 51, the outlet being controlled by a gate 52 of well known or desired construction.

60 It is often desirable to spout grain from a given bin to a number of points, such, for

example, as legs 53, 54, 55, 56 and 57, and it is also desirable to spout from a number of bins by means of the minimum amount of spouting in a manner such as will enable the simultaneous spouting of grain from 70 different bins to different legs or other points without interference. There are many limitations which make this a difficult task and which have hitherto prevented its practical accomplishment. I have solved 75 this difficult, complex problem in a very simple manner by what I term a multiple-unit spouting system.

This system comprises a number of units, each unit consisting of a main line from 80 which one or more branches extend, which in turn are provided with feeder or stub lines terminating in openings or heads positioned in such relation to the turn heads of the grain bins as to receive the grain discharged therefrom when the turn heads are positioned over the receiving openings. In this manner the least amount of spouting possible is not only made to do the most work, but it also accomplishes its purpose in such 85 manner as greatly to increase the flexibility and efficiency of the work house, and greatly to reduce the amount of labor necessary to operate the house.

The drawings illustrate an actual installation, and to make certain an understanding thereof, such as will enable others skilled in the art to which this appertains, to construct and use systems embodying my invention, I have given reference characters 95 to all parts, the multiple units being given letters A, B, C, D, E, F, G, H, J, K, L, M and N. Each spout head on each unit is given a designating number associated with the unit letter such as, for instance, A¹, E⁹, 100 M¹⁰, etc., so that a mere inspection of the drawings will enable the tracing of any spout or unit.

In order that the proportions may be better understood, it may be stated that the 110 drawings are drawn to a scale of substantially one-eighth inch to the foot.

A few illustrations of the operation of the system, it is thought will be sufficient to a complete understanding thereof without further detailed reference to the spouting units. I might here state, however, that the spouting units are preferably formed of sheet metal, and, in every instance, preferably are completely closed except at the 115 ends. This point is of practical importance, for the reason that it prevents the spreading of dust, thus lessening the danger of fires, and making the first floor more comfortable for the workmen; it also enables the use of a choke feed, that is to say: 120 enables the spouting of the grain with the spout completely full, so that a relatively slow movement thereof is sufficient to supply the elevator legs or other receiving 125 130

points adequately. Also, by the use of a choke feed, the wear on the spouts is much less. When portable spouts are employed, having the channel formed with an open top, as now in general use, these advantageous features cannot be had.

By the use of this system of spouting, as shown in Figs. 1 to 8 inclusive, the following results are accomplished:

10 Through unit A it is possible to spout grain from any of the following bins to leg 57:—bin Nos. 40, 35, 39, 38, 34, 46, 47, 44, 45.

Through unit F it is possible to spout grain from any of the following bins to

15 leg 57:—bin Nos. 4, 5, 6, 7, 8.

Through unit K it is possible to spout grain from any of the following bins to leg 57:—bin Nos. 12, 13, 14, 15, 22, 23, 24.

This makes a total of 21 bins which can 20 be spouted to leg 57 through units A, F and K.

Through unit B it is possible to spout grain from the following bins to leg 56:—bin Nos. 35, 34, 39, 40, 47, 45, 46, 38, 44.

25 Through unit G it is possible to spout grain from the following bins to leg 56:—bin Nos. 4, 5, 6, 7, 8, 9.

Through unit L it is possible to spout grain from the following bins to leg 56:—bin Nos. 12, 13, 14, 15, 16, 18, 26, 28, 25, 27, 30, 23, 24.

This makes a total of 27 bins which can be spouted to leg 56 through units B, G and L.

35 Through unit C it is possible to spout grain from the following bins to leg 55:—bin Nos. 45, 46, 47, 48, 35, 36, 42, 41, 39, 40.

Through unit G it is possible to spout grain from the following bins to leg 55:—bin Nos. 4, 5, 6, 7, 8, 9.

40 Through unit L it is possible to spout grain from the following bins to leg 55:—bin Nos. 12, 13, 14, 15, 16, 18, 26, 28, 25, 27, 23, 24.

45 This makes a total of 28 bins which can be spouted to leg 55 through units C, G and L.

Through unit D it is possible to spout grain from the following bins to leg 54:—bin Nos. 46, 47, 49, 48, 42, 40, 41, 35, 36, 37, 43.

50 Through unit H it is possible to spout grain from the following bins to leg 54:—bin Nos. 6, 7, 8, 9, 10, 11.

55 Through unit M it is possible to spout grain from the following bins to leg 54:—bin Nos. 33, 21, 20, 16, 17, 18, 19, 15, 29, 31, 30, 32, 25, 26, 27, 28.

This makes a total of 33 bins which can 60 be spouted to leg 54 through units D, H and M.

Through unit E it is possible to spout grain from the following bins to leg 53:—bin Nos. 37, 36, 41, 42, 43, 49, 48.

65 Through unit J it is possible to spout

grain from the following bins to leg 53:—bin Nos. 8, 9, 10, 11.

Through unit N it is possible to spout grain from the following bins to leg 53:—bin Nos. 16, 18, 17, 19, 20, 21, 33, 31, 32, 29, 70, 30, 26, 28.

This makes a total of 24 bins which can be spouted to leg 53 through units E, J and N.

By the use of this system the following 75 is also accomplished:

From bin No. 4 grain can be spouted to either unit F or G, reaching either leg 57, 56 or 55.

From bin No. 5 grain can be spouted to either unit F or G, reaching either leg 57, 56 or 55. 80

From bin No. 6 grain can be spouted to either unit F, G or H, reaching either leg 57, 56, 55 or 54.

From bin No. 7 grain can be spouted to either unit F, G or H, reaching either leg 57, 56, 55 or 54.

From bin No. 8 grain can be spouted to either unit F, G, H or J, reaching either leg 90 57, 56, 55, 54 or 53.

From bin No. 9 grain can be spouted to either unit G, H or J, reaching either leg 56, 55, 54 or 53.

From bin No. 10 grain can be spouted to 95 either unit H or J, reaching either leg 54 or 53.

From bin No. 11 grain can be spouted to either unit H or J, reaching either leg 54 or 53. 100

From bin No. 12 grain can be spouted to either unit K or L, reaching either leg 57, 56 or 55.

From bin No. 13 grain can be spouted to either unit K or L, reaching either leg 57, 105 56 or 55.

From bin No. 14 grain can be spouted to either unit K or L, reaching either leg 57, 56 or 55.

From bin No. 15 grain can be spouted to 110 either unit K, L or M, reaching either leg 57, 56, 55 or 54.

From bin No. 16 grain can be spouted to either unit L, M or N, reaching either leg 56, 55, 54 or 53.

From bin No. 17 grain can be spouted to 115 either unit M or N, reaching either leg 54 or 53.

From bin No. 18 grain can be spouted to either unit L, M or N, reaching either leg 56, 55, 54 or 53.

From bin No. 19 grain can be spouted to either unit M or N, reaching either leg 54 or 53.

From bin No. 20 grain can be spouted to 125 either unit M or N, reaching either leg 54 or 53.

From bin No. 21 grain can be spouted to either unit M or N, reaching either leg 54 or 53. 130

- From bin No. 22 grain can be spouted to unit K, reaching leg 57.
- From bin No. 23 grain can be spouted to either unit K or L, reaching either leg 57, 56 or 55.
- From bin No. 24 grain can be spouted to either unit K or L, reaching either leg 57, 56 or 55.
- From bin No. 25 grain can be spouted to either unit L or M, reaching either leg 56, 55 or 54.
- From bin No. 26 grain can be spouted to either unit L, M or N, reaching either leg 56, 55, 54 or 53.
- From bin No. 27 grain can be spouted to either unit L or M, reaching either leg 56, 55 or 54.
- From bin No. 28 grain can be spouted to either unit L, M or N, reaching either leg 56, 55, 54 or 53.
- From bin No. 29 grain can be spouted to either unit M or N, reaching either leg 54 or 53.
- From bin No. 30 grain can be spouted to either unit M or N, reaching either leg 54 or 53.
- From bin No. 31 grain can be spouted to either unit M or N, reaching either leg 54 or 53.
- From bin No. 32 grain can be spouted to either unit M or N, reaching either leg 54 or 53.
- From bin No. 33 grain can be spouted to either unit M or N, reaching either leg 54 or 53.
- From bin No. 34 grain can be spouted to either unit A or B, reaching either leg 57 or 56.
- From bin No. 35 grain can be spouted to either unit A, B, C or D, reaching either leg 57, 56, 55 or 54.
- From bin No. 36 grain can be spouted to either unit C, D or E, reaching either leg 55, 54 or 53.
- From bin No. 37 grain can be spouted to either unit D or E, reaching either leg 54 or 53.
- From bin No. 38 grain can be spouted to either unit A or B, reaching either leg 57, 56 or 55.
- From bin No. 39 grain can be spouted to either unit A, B or C, reaching either leg 57, 56 or 55.
- From bin No. 40 grain can be spouted to either unit A, B, C or D, reaching either leg 57, 56, 55 or 54.
- From bin No. 41 grain can be spouted to either unit C, D or E, reaching either leg 55, 54 or 53.
- From bin No. 42 grain can be spouted to either unit C, D or E, reaching either leg 55, 54 or 53.
- From bin No. 43 grain can be spouted to either unit D or E, reaching either leg 54 or 53.
- From bin No. 44 grain can be spouted to either unit A or B, reaching either leg 57 or 56.
- From bin No. 45 grain can be spouted to either unit A, B or C, reaching either leg 70 57, 56 or 55.
- From bin No. 46 grain can be spouted to either unit A, B, C or D, reaching either leg 57, 56, 55 or 54.
- From bin No. 47 grain can be spouted to either unit A, B, C or D, reaching either leg 75 57, 56, 55 or 54.
- From bin No. 48 grain can be spouted to either unit C, D or E, reaching either leg 80 55, 54 or 53.
- From bin No. 49 grain can be spouted to either unit D or E, reaching either leg 54 or 53.
- By the use of this system of spouting, as shown in Figs. 1 to 9, inclusive, it is possible, in reelevating grain, to run all of the legs simultaneously, each leg receiving grain from any bin which has a unit of spouting reaching to that bin.
- By the use of this system of spouting it is also possible for one man to do all the labor required to spout grain to all of the legs simultaneously, or otherwise, as all he has to do is to set the turn head spout on the bin bottom so that when he opens the bin bottom gate it will discharge grain into the unit of spouting which serves the leg which he desires to spout to.
- As an example, let us suppose that we wish to spout grain from bin 33 to leg 54, 100 and, at the same time, to spout grain from bin 16 to leg 53 (see Fig. 1). The first operation would be to set the turn head spout on bin bottom 33 to a position as shown in plan by dotted lines. Then the gate on the 105 bin bottom would be opened and the grain would pass through unit M to leg 54. The path it would take can be followed by looking at Figs. 5 and 6, which show the elevations of spouting unit M. No further attention would have to be paid, except to regulate the feed gate on the elevator leg. A typical leg feed gate is indicated by Nos. 95 and 96 in Fig. 12. The aforementioned operations would also have to be performed 110 to spout grain from bin 16 to leg 53, the grain passing through unit N, elevations of which are shown in Figs. 7 and 8.
- Suppose we were now spouting grain to leg 54 and to leg 53, as before mentioned, 120 and we now, and at the same time, wished to spout grain to legs 57, 56 and 55 from bins 47, 44 and 45 respectively. The only labor required to do this would be to go through the operations as before mentioned, to spout grain from bin 33 to leg 54, the grain, in this case, passing through units A, B and C respectively.
- If the well-known system of spouting by the means of portable spouts from the bin 130

bottom turn head spouts to gratings in the first floor were used, it would require much labor to erect and take down and move the portable spouts around again, and the same 5 results could not even then be accomplished, by reason of the fact that oftentimes the portable spouts would not pass each other, thereby keeping one or more legs idle while the other or others were being run. If the 10 well-known system of using an individual fixed spout from each bin bottom turn head spout to a convenient height above the first floor were used, so that from there a short portable spout could be made to serve several 15 floor gratings, the flexibility of the house would not be as great because the short portable spouts would not in all cases pass each other. By using an individual spout as before mentioned much more spouting would 20 be required, the cost would be greater and the results less.

As another example, suppose we wished to 25 spout grain simultaneously, or otherwise, from bins 12, 15, 27 and 26 to legs 55, 57, 54 and 53 respectively. The only work required to accomplish this would be to set 30 the bin bottom turn heads, open the bin bottom gates and regulate the leg feed gates as before mentioned, the grain passing through units L, K, M and N respectively.

In all cases, it is understood that the leg, or belt or screw conveyer, as the case may be, must be started before spouting is commenced.

35 In all cases it is also understood that the spout heads must be made large enough so that when grain is spouted into them from the turn head, the grain will not pass over the top or sides.

40 Referring to Figs. 9 to 12, inclusive, let us suppose that it is desired to spout grain from certain of the bins to either the shipping leg No. 58, or to the belt conveyer No. 97, simultaneously. By the use of my system the following results are accomplished:

45 Through unit R it is possible to spout grain from any of the following bins to shipping leg No. 58:—bin Nos. 59, 60, 61, 62, 63, 64, 65, 66.

50 Through unit U it is possible to spout grain from any of the following bins to shipping leg No. 58:—bin Nos. 79, 80, 72, 78, 71, 77, 70, 76.

55 Through unit V it is possible to spout grain from any of the following bins to shipping leg No. 58:—bin Nos. 67, 73, 68, 74, 69, 75.

60 Through unit X it is possible to spout grain from any of the following bins to shipping leg No. 58:—bin Nos. 85, 93, 84, 92, 91.

65 Through unit Y it is possible to spout grain from any of the following bins to shipping leg No. 58:—bin Nos. 82, 88, 83, 89, 90.

Making a total of 32 bins which can be spouted to shipping leg No. 58, through units R, U, V, X and Y.

Through unit S it is possible to spout grain from any of the following bins to belt conveyer No. 97:—bin Nos. 64, 63, 62, 61.

Through unit T it is possible to spout grain from any of the following bins to belt conveyer No. 97:—bin Nos. 72, 71, 70, 69.

Through unit W it is possible to spout grain from any of the following bins to belt conveyer No. 97:—bin Nos. 78, 77, 76, 75.

Through unit Z it is possible to spout grain from any of the following bins to belt conveyer No. 97:—bin Nos. 84, 92, 91, 80 90, 83, 89.

Making a total of 18 bins shown which can be spouted to belt conveyer No. 97 from the right hand side of floor gratings Nos. 98 and 99 through units S, T, W and Z. 85

On account of lack of space I have not shown all of the bins which could also be spouted to belt conveyer No. 97 from the left hand side of floor gratings Nos. 98 and 99, but probably another 18 bins could 90 be spouted from the left hand side, making a probable total of 36 bins.

It will also be noted that it is possible to spout grain from any bin shown, to either the shipping leg or the belt conveyer 95 simultaneously, which we suppose is desired.

The description of the working of the system previously described in Figs. 1 to 8, inclusive, also applies to the working of the system in Figs. 9 to 12, inclusive, 100 and the same benefits and results are obtained, the only difference being that at the discharge end of units S and T, U, V, X and Y, and Z, one short portable spout is used to complete the connection to the 105 floor gratings which, in turn, spout to the shipping leg or belt conveyer as shown in Fig. 12.

This disclosure will readily suggest to others skilled in the art to which this 110 application pertains, various modified structures whereby the substantial objects and purposes of my invention may be attained, and for this reason I do not wish to be limited to the exact constructions shown and described except only as may be necessary by limitations in the hereunto appended claims.

In all cases it is understood that the spouts must be pitched at least at an angle sufficient for the grain to flow satisfactorily. 120

In all cases it is also understood that all spouts are to be supported as may be necessary.

By the use of this system it is also possible to blend the grain from the different 125 bins reached by a unit or number of units of spouting which ultimately reach the same fixed discharge point. This can be accomplished by partially opening the bin bottom gates of a plurality of bins as may be de- 130

sired. For example, it is possible to blend grain from bins Nos. 4, 5, 6, 7, and 8 and bins Nos. 40, 35, 39, 34, 38, 47, 46, 45 and 44 through units F and A, whose ultimate discharge point is leg No. 57.

This could not be accomplished by the old methods of spouting.

I claim—

1. A grain elevator work house, or building of like character, comprising a plurality of grain bins having discharge openings, points of delivery for the grain, and a plurality of multiple-unit spouts connecting said bins and said delivery points, each 10 unit serving a number of bins, and turn

head spouts on the grain bin bottom, swingable to discharge into a plurality of spout units.

2. In a grain elevator work house, or building of like character, the combination 20 of a plurality of grain bins having discharge openings, points of delivery for the grain, and a plurality of multiple-unit spouts connecting said bins and said delivery points, each unit serving a number of bins, 25 and means on each grain bin operable to discharge into a plurality of spout units.

In testimony whereof, I have hereunto set my hand this 21st day of May, 1918.

WILLIAM SUNDBERG.

Copies of this patent may be obtained for five cents each, by addressing the "Commissioner of Patents, Washington, D. C."
